UNITED STATES PATENT OFFICE.

WALTER G. CLARK, OF SEATTLE, WASHINGTON, ASSIGNOR TO THE CLARK ELECTRIC AND MANUFACTURING COMPANY, A CORPORATION OF NEW YORK.

INSULATOR-CLAMP.

No. 851,222.

Specification of Letters Patent.

Patented April 23, 1907.

Application filed September 2, 1905. Serial No. 276,886.

To all whom it may concern:

Be it known that I, WALTER G. CLARK, a citizen of the United States, and a resident of Seattle, county of King, State of Washington, have invented certain new and useful Improvements in Insulator-Clamps, of which the following is a specification accompanied by drawings.

This invention relates to insulator clamps and its objects are to improve upon said devices and increase their strength and efficiency with reduction of cost.

Another object of the invention is to enable a wire to be firmly clamped upon an insulator and at the same time afford provision for expansion and contraction of the wire without injuring the insulator or the clamp.

Further objects of the invention will hereinafter appear and to these ends the invention consists of an insulator clamp for carrying out the above objects, embodying the features of construction, combinations of elements, and arrangement of parts, having the general mode of operation substantially as hereinafter fully described and claimed in this specification and shown in the accompanying drawings, in which,—

Figure 1 is a top plan view of one form of the invention; Fig. 2 is a longitudinal sectional elevation of the same with the parts in one position; Fig. 3 is an elevation partly in longitudinal section with the parts in another position; Fig. 4 is a perspective view of one member of one of the clamps; Fig. 5 is a top plan view of a modification of the invention; Fig. 6 is a longitudinal sectional elevation of Fig. 5; Fig. 7 is an elevation partly in longitudinal section with the parts in a different position from that shown in Fig. 6; and Fig. 8 is a perspective view of one of the modified forms of insulator clamps. Fig. 9 is a vertical sectional detail view of a portion of the insulator and a modified form of clamp. Fig. 10 is a longitudinal sectional view of Fig. 9.

Referring to the drawings, A represents a suitable insulator provided with a cap B, which may be in one or more portions, in this instance the body and the cap being made all in one solid piece. The cap is provided with a groove D for the wire E, and in accordance with this invention insulator clamps comprising co-operating members F and G are adapted to be clamped to a wire or conductor and

suitably interlocked with the insulator cap in such manner that the wire is secured in position, but may expand and contract in accordance with changes of temperature without breaking the insulator and without injuring the clamps. The wire or conductor is so held that it cannot move longitudinally nor can it rise out of the groove in the cap.

In the form of the invention shown in Figs. 1 to 4 inclusive, the cap of the insulator is provided with hollowed circular sockets H at each end of the groove D in the sides of the cap and the clamps are provided with hemispherical bearing portions I which are adapted to co-operate with the sockets H, thus forming ball and socket joints between the insulator and the clamps.

The clamps comprise co-operating members F and G provided in addition to the balls I, with longitudinal grooves J for the wire, and pins or projections K extending from the body portion L. The body portions L are also provided with apertures O so that when the two members F and G are placed opposite each member, the projections K enter the apertures O. The members F and G are secured together by suitable means as the nuts P adapted to be screwed upon the screw-threaded ends of the projections K. The clamping members F and G are also preferably provided with suitable eyes or loops S to which are connected the bands T lying in the grooves V on the outside of the cap B, whereby the clamps are prevented from tipping sideways under strains. The bands T, and clamps at each end form two halves of the complete clamp which co-operate to hold the wire or conductor in place. With this construction the clamps may be used either with or without the retaining bands.

The sockets H are of a slightly greater diameter than that of the hemispherical portions I on the clamps, so that the balls formed by the portions I have a certain amount of play in the sockets to permit the wire or conductor E to sag as indicated in Fig. 3. According to this construction it will be seen that the weight of the wire is thrown upon the insulator and not upon the clamps themselves which is a great advantage.

In Figs. 5 to 8 inclusive, a modification is shown in which the sides of the cap B' are provided with angular grooves H' at each end of

the slot D and the members F' and G' of the clamps are provided with wedge shaped portions I' co-operating with the angular groove H'. The angle of the groove H' is slightly 5 greater than the angle of the wedge I' so that the insulator clamps may have a certain amount of play to enable the wire to sag as indicated in Fig. 7 without throwing the strain and weight of the wire upon the clamps. 10 The clamps F' and G' are also provided with eyes S' for the bands T so that if desired, said bands T may be used in connection with the clamps.

In Figs. 9 and 10 the clamping members F² 15 and G² are shown provided with rounded ends which fit the rounded sockets I² in the insulator. The sockets I² in this form of insulator are also curved in a horizontal plane, so that the clamping members are correspondingly curved to co-operate therewith. 20

Obviously some features of this invention may be used without others and the invention may be embodied in widely varying forms, therefore, without limiting the invention to the devices shown and described, and without enumerating equivalents, 25

I claim and desire to obtain by Letters Patent the following:

1. The combination with an insulator and 30 conducting wire, of detachable clamps for said wire adapted to hold the wire in position, said clamps comprising co-operating grooved members provided with bearing portions adapted to co-operate with sockets on the 35 outside of the insulator.

2. The combination with an insulator, of 40 detachable insulator clamps each comprising a plurality of grooved members adapted to be clamped to the wire and having bearing portions movably supported in sockets on the outside of the insulator.

3. The combination with an insulator, of 45 insulator clamps each comprising a plurality of grooved members adapted to be clamped to the wire conductor and having bearing portions movably supported in sockets on the outside of the insulator and arranged for the attachment of holding bands to surround at least a portion of the insulator, whereby the 50 clamps may be connected together.

4. The combination with a grooved insulator and conductor, of detachable means movably secured to the insulator for clamping the conductor, said means consisting of two co-operating clamping members enclosing 55 the insulator, and means for securing said members to each other and to the conductor.

5. The combination with a grooved insulator and conductor, of detachable means 60 movably secured to the insulator for clamping the conductor, said means consisting of bands at each side of the insulator provided with co-operating clamps at each end adapted to embrace the conductor, and means for 65 securing said clamps to each other.

6. The combination with a conducting wire and an insulator provided with a groove, 70 sockets at each end of said groove, and clamps secured to said wire and adapted to engage said 75 sockets.

7. The combination with a conducting wire and an insulator provided with a groove, 80 sockets at each end of said groove, clamps secured to said wire and adapted to engage said 85 sockets, and bands secured to said clamps, whereby the clamps are prevented from tipping sideways under strains.

8. The combination with a conducting wire and an insulator provided with a transverse groove, hollowed sockets at each end of 85 said groove, and clamps secured to said wire and adapted to engage said hollowed sockets.

9. The combination with a conducting wire and an insulator provided with a transverse groove, hollowed sockets at each end of 90 said groove, clamps secured to said wire and adapted to engage said hollowed sockets, and clamps provided with bearing portions secured to said wire and adapted to co-operate 95 with said sockets for securing the wire to the insulator.

In testimony whereof I have signed this specification in the presence of two subscribing witnesses.

WALTER G. CLARK.
